UNITED STATES PATENT OFFICE.

CHARLES EDWARD MORGAN, OF RINCON, NEW MEXICO.

CABLE-CLIMBING DEVICE FOR MINERS.

1,311,084.

Specification of Letters Patent.

Patented July 22, 1919.

Application filed March 18, 1919. Serial No. 263,434.

To all whom it may concern:

Be it known that I, CHARLES E. MORGAN, a citizen of the United States, residing at Rincon, in the county of Dona Ana and State of New Mexico, have invented new and useful Improvements in Cable-Climbing Devices for Miners, of which the following is a specification.

This invention relates to cable hoists, particularly to cable climbing devices, and has for its object the provision of a device which is manually operated and by means of which an operator may quickly and easily ascend or descend a cable hanging vertically, the device being particularly adapted for use by prospectors and miners for enabling them to gain access to veins of ore located in the walls of precipices, cañons and the like.

An important and more specific object is the provision of a device of this character comprising a supporting frame having disposed therein a plurality of drums engaging the cable and provided with other drums about which is trained a chain which is manually movable for rotating the drums to cause the device to travel up or down upon the cable, the invention further comprising the provision of brake means whereby descent of the device may be accomplished at any desired speed at the will of the operator.

A further object is the provision of a device of this character embodying a platform upon which a plurality of operators may be seated in safety while working upon a precipitous wall.

Another object is the provision of a device of this character including in its construction a safety catch which will prevent accidental descent, the catch being releasable whereby the device may be permitted to descend gravitationally, the descent being controlled by a brake drum.

An additional object is the provision of a device of this character which will be comparatively simple and inexpensive in manufacture, highly efficient in service, durable in use and a general improvement in the art.

With the above and other objects and advantages in view, the invention consists in the details of construction to be hereinafter more fully described and claimed, and illustrated in the accompanying drawings in which:—

Figure 1 is a front elevation of the device,

Fig. 2 is a side elevation,

Fig. 3 is a longitudinal sectional view looking toward one side plate of the device,

Fig. 4 is a similar longitudinal sectional view looking at the other side plate of the device,

Fig. 5 is a longitudinal sectional view taken at right angles to Figs. 3 and 4, and

Fig. 6 is a cross sectional view taken above the platform.

Referring more particularly to the drawings, the numerals 10 and 11 designate upper and lower housing members which are connected by side plates 12 and 13 suitably bolted thereto. The bolts 14 securing the side plates to the lower housing member 11 extend beyond the side members as shown for a purpose to be described.

Extending transversely through the lower housing member 11 and through the side plates 12 and 13 is a shaft 15 upon which is journaled a drum 16 having a serrated periphery. Also mounted upon the shaft 15 at one side of the drum 16 is a relatively large sprocket 17 and disposed at the other side of the drum 16 is a brake drum 18. The drum 16, sprocket 17, and brake drum 18 are either formed integrally or are secured together so that they will rotate together upon the shaft 15. The ends of the shaft 15 extend beyond the side plates 12 and 13 and are preferably provided with nuts 19.

A pair of platforms 20 are arranged at opposite sides of the frame and have their arms 21 arranged in straddling relation to the side plates 12 and 13 and apertured for engagement upon the projecting ends of the shaft 15. When the arms 21 of the platforms are thus disposed in position and the nuts 19 are applied upon the projecting ends of the shaft 15 the platforms will be firmly held in position. The platforms are maintained in normally horizontal position by engagement with the edges of the lower housing member 11.

Extending transversely through the upper housing member 10 and the side plates 12 and 13 is a shaft 22 upon which is journaled a drum 23 having a serrated surface. The cable 24 extends through holes 25 formed in the upper and lower housing members 10 and 11 and is trained about the drums 23 and 16, as shown, the serrations on the peripheries of these drums preventing slipping of the cable. Also disposed upon the shaft 110

22 and rotatable with the drum 23 is a relatively large sprocket 26 about which is trained a chain 27 which is also trained about the sprocket 17. By virtue of this 5 chain and sprocket connection the drums 16 and 23 will rotate in the same direction at the same speed.

Extending transversely through the side plates 12 and 13 is a rod 28 upon which is 10 pivotally mounted a lever 29 to one end of which is connected a brake band 30 which extends partially around the brake drum 18 and which has its other end secured to a post 31 extending inwardly from the side plate 15. When pressure is applied upon the lever 29 the band 30 will be pressed into engagement with the drum 18 so as to limit the speed of rotation of the drum 18, drum 16 and sprocket 17.

20 In order to provide a safety catch I provide a pawl 32 pivoted upon the rod 28 adjacent the side plate 13 and arranged with its active ends normally engageable with the teeth of the sprocket 17.

25 The operation of the device is as follows:—The upper end of the cable 24 is suitably secured at the top of a precipitous wall to be operated upon and the lower end has secured thereto a suitable heavy weight in 30 order that the cable will be held taut at all times. With the parts of the device arranged as shown and described, the operators 1 or 2, seat themselves upon the platforms 20. The operator upon one platform 35 pulls upon the chain 27 in a downward direction and the operator upon the opposite platform pulls upon the chain in an upward direction in order to effect rotation of the sprockets 17 and 26 which will result in 40 rotation of the drums 16 and 23. As these drums rotate the device will travel upwardly along the cable. As the sprocket 17 rotates it rides under the pawl 32 which 45 gravitationally bears against the teeth of the sprocket. In case the operators cease to pull upon the chain 27 any tendency toward reverse movement of the sprocket 17 will result in engagement of one of the teeth thereof with the pawl 32 so as to prevent the 50 device from descending the cable. When the operators are seated upon the platform 20, the projecting ends of the bolts 14 will serve as footholds whereby they may brace themselves so as to pull more effectually 55 upon the chain 27. It will thus be seen that by pulling upon the chain 27 the cable may be quickly and easily climbed and that as soon as the device has reached the desired height the pawl 32 will operate to prevent 60 descent thereof so that the operators may conveniently work upon the wall before them. For the sake of convenience I preferably employ a bag or other similar receptacle 33 secured upon either of the side 65 plates and adapted for holding tools or for

holding ore removed from the wall. When it is desired to descend the cable, it is first necessary that an operator grasp the lever 29 and exert considerable pressure thereon so as to contract the band 30 about the 70 brake drum 18, after which the pawl 32 is swung upon its pivot out of engagement with the teeth of the sprocket 17. By then relieving a portion of the pressure upon the lever 29 the device may be allowed to descend the cable gradually.

75 From the foregoing description and a study of the drawings it will be apparent that I have thus provided a simple and efficient device by means of which ascent or descent of a cable may be quickly and easily made, the construction of the device being such that it will be safe in its operation and will remain in any desired position so that operators seated thereon may work safely 80 upon the face of a wall. While the invention is primarily designed for the use of prospectors and miners in working upon precipitous walls or gaining access to veins of ore therein, it will be readily understood 85 that the device is equally adapted for use by painters and in fact by others finding it necessary to work upon precipitous walls.

90 While I have shown and described the preferred embodiment of the invention, it will 95 of course be readily understood that I reserve the right to make such changes in the form, construction and arrangement of parts as will not depart from the spirit of the invention nor the scope of the subjoined 100 claims.

Having thus described my invention I claim:—

1. A device of the character described comprising upper and lower housing members, side plates secured to and connecting said members, drums journaled in said upper and lower housing members, sprockets journaled within said housing members and rotatable with said drums, a chain trained about said sprockets, a cable extending through said housing members and trained about said drums, a rod extending transversely between said side plates, a pawl pivoted upon said rod and having its active end engageable with the teeth of the lower sprocket, and means for controlling the speed of rotation of said drums.

110 2. A device of the character described comprising upper and lower housing members, side plates secured to and connecting said members, shafts extending transversely through said housing members and through said side plates, drums journaled on said shafts, a sprocket wheel journaled on each 115 shaft and secured to the adjacent drum, a chain trained about said sprockets, a brake drum journaled on the lowermost one of said shafts and rotatable with the drum and sprocket thereon, a rod extending trans- 120

125 130

versely of said side plates, a pawl pivoted upon said rod and having its active end engageable with the teeth of the lowermost sprocket, a lever pivoted upon said rod, and 5 a brake band secured at one end to said lever and having its other end rigidly secured to one of said side plates.

3. A device of the character described 10 comprising upper and lower housing members, side plates secured to said members, transverse shafts extending through said upper and lower housing members and through said side plates, cable engaging drums journaled upon said shafts, sprockets

journaled upon said shafts and rotatable 15 with said drums, a chain trained about said sprockets, and a pair of platforms disposed at opposite sides of the device and including arms straddlingly engaging said side plates, the ends of the lowermost transverse shaft 20 projecting beyond said side plates and through said arms, said platforms having their lower edges engaging the sides of the lower housing member whereby to maintain said platform in horizontal position. 25

In testimony whereof I affix my signature.

CHARLES EDWARD MORGAN.
